ROLLER SET GAUGE

Auburn Taylor, Charleston, W. Va.

Application October 28, 1939, Serial No. 301,702

4 Claims. (Cl. 33—182)

The present invention relates to a roller set indicator and more particularly to new and improved means for determining the correct setting of certain of the roller members in a rotary printing press.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawing, referred to herein and constituting a part hereof, illustrates one embodiment of the invention, and together with the description, serves to explain the principles of the invention.

Of the drawing:

Figure 1 is a top plan view of a typical and illustrative embodiment of the present invention;

Figure 2 is a fragmentary detailed plan view of the embodiment shown in Figure 1;

Figure 3 is a sectional view showing the roller set indicator of the present invention positioned between two members of the inking system of a rotary printing press;

Figure 4 is a sectional view taken on the line 4—4 of Figure 2; and

Figure 5 is an exploded view in perspective of the slide member forming part of the present embodiment.

The present invention has for its object the provision of a novel and improved gauge for effectively ascertaining the degree of pressure or the position of two rollers of a printing press. A further object of the invention is the provision of an improved gauge for determining the correct setting of the inking rollers in a rotary newspaper press. The invention also provides a simple, effective and accurate means of initially setting the inking rollers of a rotary printing press so that the correct inking of the plates will be assured.

Referring now in detail to the illustrative embodiment of the invention as shown in the accompanying drawing, the gauge comprises a relatively long, thin and narrow metal strip or blade 10 which may conveniently be formed of steel, and is adapted to be inserted between two rotary members of a rotary printing press. As shown in Figure 3, the gauge is inserted between a plate cylinder 11 and a rubber form roller 12, but the gauge is also useable between any two rotary

members, one of which is provided with a resilient surface. The blade 10 has a handle portion 14 and beyond that is provided with a narrow, longitudinal groove 15 extending for the major portion of the length of the strip 10 and centrally thereof, and the depth of this groove as well as the thickness of the strip 10 is preferably uniform throughout.

The bottom of the groove 15 is preferably flat 10 and smooth, and the pressure between the cylinder 11 and roller 12 forces the inked surface of the form roller below the top surface of the strip 10 and into contact with the bottom of the groove 15, the width of the area of contact being determined by the pressure between the roller 12 and cylinder 11, and where the roller 12 is in contact with the bottom of the groove 15, a stripe of ink is left in the groove 15 corresponding in width to the roller pressure.

20 Means are provided for measuring the width of the stripe of ink transferred to the bottom of groove 15, and these means may be calibrated in arbitrary units of length or in units of pressure. As embodied, an indicator slide 18 is movable 25 along the strip 10 and is shown in detail in Figures 2, 4 and 5. This indicator comprises a rectangular base 20, a cover plate 21 and an index plate 22. The base plate 20 is channeled to receive and slide along the blade or strip 10, and base 20 and plate 21 are rigidly held together 30 by rivets passing through the holes 23. The index plate 22 is formed with a sharply bent edge 25 and with a long slot 26 through which passes a screw 27 permitting the slide 22 to be moved along the parts 20 and 21 without angular movement, and a knurled nut 28 is provided to hold the index slide 22 in any desired position.

The cover plate 21 is provided with a slot 29 adapted to overlie the groove 15, and one end of the slot 29 is formed with a shoulder 30 which may be set against one edge of the ink stripe on the bottom of the groove 15. Index slide 22 is similarly provided with a shoulder 32 and the narrower portion of the index plate 22 is parallel 35 and preferably aligned with the nearer edge of the groove 15 and may be calibrated with suitable index marks in linear or pressure units.

40 By relatively moving the index plate 22 with reference to the remainder of the slide 18, the space between the shoulders 30 and 32 may be 45 adjusted to form a definite gap corresponding to the correct or normal setting of the roller 12, and after the stripe has been marked on the bottom of the groove 15 the shoulders 30 and 32 are brought over the edges of the stripe so that

the width of the stripe may be compared with the spacing of the shoulders.

In the use of the present invention, the roller 12 is freed from the cylinder 11 with its grooved side facing the roller 12, and the roller 12 is then moved into operative position with reference to the cylinder 11, and correctly adjusted for operation. The inked surface of the form roller 12 is squeezed into groove 15 and transfers a stripe of ink to the bottom of the groove. The pressure on the roller 12 is then released, as by releasing the roller sockets in the usual manner, the blade or strip 19 is removed from between the cylinder 11 and the roller 12, and the slide 18 may then be moved until one shoulder 30 or the other shoulder 32 is in register with one edge of the stripe. If the other shoulder registers with the other edge of the stripe, or if the stripe is of the correct width as measured on the scale, the setting of the roller is known to be correct, and when the roller is replaced in its sockets and locked up for printing, its pressure will be known to be correct.

If the setting is incorrect, of course the roller may be adjusted to increase or decrease its pressure against the cylinder 11. Of course, the roller set indicator of the present invention may also be used with rollers which are not mounted in sockets so that they may be returned to an original adjustment, and with these rollers the roller is released after the impression has been taken in the groove 15 and the roller is again adjusted to a similar position for operation.

The invention in its broader aspects is not limited to the specific mechanisms shown and described but departures may be made therefrom

within the scope of the accompanying claims without departing from the principles of the invention and without sacrificing its chief advantages.

5. What I claim is:

1. A gauge for setting inking rollers including in combination a blade-like member having a surface against which the inking roller is pressed with a definite pressure, an indexing member movable along the surface and means for spacing the indexing member from the surface to prevent smudging of the impression of the roller on the surface.

15 2. A gauge for setting inking rollers including in combination a blade-like member, a narrow flat surface recessed in said member and an indexing member slidable along the blade-like member for measuring the stripe made by an inking roller pressed against the surface.

20 3. A gauge for setting inking rollers including in combination a blade-like member, a narrow groove in said member having a flat surface, an index slide movable along the blade and out of contact with the surface for measuring the stripe made by an inking roller pressed against the surface.

25 4. A gauge for setting inking rollers including in combination a blade-like member, a narrow groove in said member having a flat surface, an index slide movable along the blade and out of contact with the surface for measuring the stripe made by an inking roller pressed against the surface, said index slide having a movable part which can be set to indicate the correct width for a standard position of the inking roller.

AUBURN TAYLOR.
